(57) **CLAIM**

The ornamental design for a hair growth stimulator, as shown and described.

DESCRIPTION

FIG. 1 is a perspective view of the hair growth stimulator in accordance with the present design;
FIG. 2 is a front view of the hair growth stimulator in accordance with the present design;
FIG. 3 is a back view of the hair growth stimulator in accordance with the present design;
FIG. 4 is a right view of the hair growth stimulator in accordance with the present design;
FIG. 5 is a left view of the hair growth stimulator in accordance with the present design;
FIG. 6 is a bottom view of the hair growth stimulator in accordance with the present design; and,
FIG. 7 is a top view of the hair growth stimulator in use in accordance with the present design.
The broken line shown in the drawings is included for the purpose of illustrating portions of the hair growth stimulator and forms no part of the claimed design.
